UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER WITH TEETH IN AN ARC.

1,332,774.

Specification of Letters Patent.

Patented Mar. 2, 1920.

Application filed July 18, 1918. Serial No. 245,565.

To all whom it may concern:

Be it known that I, EDWARD S. STIMPSON, of Hopedale, in the county of Worcester and State of Massachusetts, have invented a new 5 Feeler with Teeth in an Arc, of which the following is a specification.

The new feeler mechanism includes a sliding and swinging feeler which slides forward and back during the normal running 10 of the loom and which tends to move lengthwise of the bobbin being restrained from such movement by the weft on the bobbin. When, however, the weft approaches exhaustion the feeler tip encounters the smooth 15 surface of the bobbin and slips along the bobbin, the feeler as a whole then swinging laterally. This lateral movement is utilized to set into action a train of weft replenishing mechanism with the result that the 20 nearly depleted bobbin (or the shuttle carrying it) is ejected and a filled bobbin (or a shuttle carrying a filled bobbin) is brought into action. Except in the respects to be particularized the feeler mechanism 25 herein set forth is similar to that illustrated and described in Letters Patent of the United States, Number 1,309,226, dated July 8, 1919. The present improvement relates to the feeler tip and its relation to the laterally 30 slipping feeler arm and to the bobbin and the weft carried thereby.

The improvement is illustrated in the accompanying drawings in which—

Figure 1, is a plan view of so much of 35 the detecting side of the loom as is necessary for an understanding of the improvement. In this figure the front walls of the shuttle and of the shuttle box are shown in section, and the parts are shown in the position 40 which they occupy just as the weft first encounters the feeler tip during the forward swing of the lay. Figs. 2, 3 and 4, are views of the feeler tip and of a portion of the weft and of the bobbin on an enlarged 45 scale illustrating their relation at different stages of the operation of the loom. Fig. 2, shows the initial contact between the weft and feeler tip. Fig. 3, illustrates approximately the condition which occurs following 50 the encounter of weft and feeler tip, indicating a penetration of the teeth into the weft. Fig. 4, illustrates the conditions following the encounter between the feeler tip

and the bare bobbin. Fig. 5, is a detailed vertical section in the plane indicated in the line 5—5 in Fig. 2.

The feeler comprises a feeler arm A, and a feeler tip B. The feeler arm is mounted so as to both slide and swing and it is shown as inclined to the fore and aft swing of the lay and with the feeler tip offset laterally inward as compared with the forward end of the feeler arm, in this respect being similar to the feeler arm set forth in said patent. As a consequence of this disposition of the feeler arm the impact of the forwardly moving bobbin tends to swing the feeler arm laterally inward, that is to say toward the middle of the loom and the tip of the bobbin C, and away from the butt of the bobbin. So long, however, as weft D, is present on the bobbin opposite the feeler tip the engagement of the weft with the feeler tip teeth E, prevents such lengthwise slipping. Fig. 3, illustrates to an exaggerated degree, 75 for the sake of clearness, a penetration of the teeth E, into the weft D, to prevent the slipping of the tip lengthwise of the bobbin C.

When, however, the feeler tip teeth encounter the smooth surface of the bare bobbin, as indicated by dotted lines in Fig. 4, the impact of the bobbin on the inclined feeler causes the feeler to swing and the teeth E, to slip along the bobbin to a position indicated by full lines in Fig. 4. This lateral swing is utilized to set the weft replenishing train into action.

As thus far referred to the organization and mode of operation are similar to those of the aforesaid patent. In accordance with the present improvement, the feeler tip B, is rigidly and immovably secured within the forked free rear end of the feeler arm A, by a screw F, as shown in Fig. 5. The feeler tip has a plurality of teeth E, eight being shown. All of the teeth which ever come in contact with the bobbin are blunt and rounded so that there is no danger of either cutting the weft or scratching the bobbin. 100 The outer ends of the teeth are not in the same plane but are disposed at different distances from a plane parallel with the axis of the bobbin. This is accomplished by arranging the ends of the teeth in the arc of 105 a circle. The arc of the circle in which the

rear ends of the teeth are arranged is convex toward the bobbin as shown in Figs. 2, 3 and 4, so that the teeth are at varying distances from the bobbin, and in the normal position 5 of rest shown in Figs. 1 and 2 the middle teeth in the arc are nearer the surface of the bobbin and of the weft than are the outer or end teeth of the arc. This disposition of the teeth is such that enough of them contact 10 with the weft so that there is adequate engagement to prevent premature slipping of the feeler tip lengthwise of the bobbin. When, however, the bobbin is bare no more than two of the feeler teeth can contact with 15 the bobbin at any one time; and, as the feeler tip moves inwardly its teeth roll along the surface of the bobbin as indicated in Fig. 4, different teeth thus successively contacting with the bobbin. This tooth disposition 20 is of particular importance because the surface of the bobbin may not be smooth or true and hence with all or most of the teeth in contact with the bobbin the action of the feeler at the critical stage may not be 25 prompt. With the present improved tooth organization irregularities of the bobbin do not interfere with the instant action of the feeler tip at the critical time.

The accompanying drawings illustrate 30 only enough of the feeler supporting and coöperating mechanism to enable the sliding and swinging movements of the feeler arm to be understood since in these respects the mechanism is identical with that shown 35 in the aforesaid patent. The feeler arm A, is mounted on a bracket I, attached to a lateral extension J, of the breast beam. A rock shaft K, is journaled to the forward end of the bracket turning on a vertical axis. 40 This rock shaft has a through-aperature through which the front end of the feeler arm extends and slides. At its rear end the feeler arm extends through a broad passage-way in the bracket, the margins of this passage-way being indicated by the dotted lines L, L. The top of this passage-way is closed 45 by a cap M, which with the bottom of the bracket confines the feeler arm against vertical movement. Secured to the feeler arm near 50 is middle is a slide N, which slides on horizontal ways O, of the bracket. A spring Q, surrounds the feeler arm between the slide N, and the rock shaft K, and normally holds the feeler arm in its rearward position 55 with the slide against the shoulders of the bracket which support the cap M. The feeler arm is also maintained by the spring against the outer wall L, of the passage-way. The rock shaft K, is offset laterally 60 and outwardly with respect to the passage-way so that the feeler arm stands at an angle to the fore and aft swing of the lay and the bobbin (or the weft thereon) encounters the tip along a fore and aft path 65 nearer the tip of the bobbin than a parallel

path intersecting the rock shaft. So long as the weft on the bobbin encounters the teeth of the tip the resistance thus offered prevents any slipping of the tip lengthwise of the bobbin. Accordingly as the lay moves 70 forward after the first encounter of the weft with the tip there is no sliding of the tip on the weft; but during the completion of the forward movement of the bobbin the feeler arm is moved forwardly compressing the 75 spring Q. During this normal action there is a slight inward swing (to the right) of the feeler arm permitted by the turning of the rock shaft. When the bobbin is bare opposite the feeler tip there is a further inward lateral swing of the feeler arm to the right and this additional swing is utilized to set in action the train of weft replenishing mechanism.

This functional swing of the feeler arm 85 under the impact of the bare bobbin causes the feeler arm to encounter a controller X, and move it laterally inward. This controller is mounted in a transverse guide-way of the bracket J, as shown in dotted lines 90 and it has a slot Z, through which the feeler arm passes. This slot is sufficiently wider than the width of the feeler arm so that the normal swing of the feeler arm has no effect 95 on the controller. When, however, the functional swing of the feeler arm is imparted to it by the lengthwise movement of the feeler tip along the bobbin the controller is slid laterally inward. This lateral movement of the controller is utilized to bring 100 about weft replenishment as explained in detail in the aforesaid patent. After the functional action has occurred a fixed cam W, on the bracket acts upon a projection on the feeler arm to restore the feeler arm to 105 its normal position as it retreats under the influence of the spring Q.

The weft D, is so wound on the bobbin that there is a sufficient amount to continue 110 the weaving after the feeler tip has performed its functional slip and until weft replenishment has been effected.

It will be noted from the drawings that the arc of the points of the teeth is eccentric to the axis of the rock-shaft K, in all 115 positions of the feeler arm, the radius of the arc being less than that of the feeler arm as a whole.

I claim:—

1. A laterally slipping feeler arm having 120 a rigidly attached tip offset laterally with respect to its pivot, said tip having a plurality of bobbin and weft engaging teeth with their tips at different distances from the bobbin and arranged in an arc of a circle eccentric to the pivot of the feeler arm.

2. A laterally slipping feeler arm having 125 a rigidly attached tip with a plurality of bobbin and weft engaging teeth with their 130

tips at different distances from the bobbin and arranged in an arc of a circle eccentric to the pivot of the feeler arm.

3. A laterally slipping feeler having a plurality of bobbin and weft engaging teeth with their tips arranged in an arc of a circle convex toward the bobbin.

4. A laterally slipping feeler having a

plurality of bobbin and weft engaging teeth with their tips at varying distances from the bobbin, the middle teeth in the normal position of rest of the feeler being nearer the bobbin than the end teeth.

In witness whereof I have hereunto signed my name.

EDWARD S. STIMPSON.
